DEVICE FOR ATOMIZING LIQUID INSECTICIDES OR FUNGICIDES

Hubert D. Bennett, Toledo, Ohio, assignor to
Plaskon Company, Incorporated, Toledo, Ohio,
a corporation of Delaware

Application January 6, 1937, Serial No. 119,306

1 Claim. (Cl. 299—95)

This invention relates to atomizers, and more particularly to a device for atomizing liquid insecticides or fungicides under the pressure of a gas dissolved in such liquids.

5 It is customary to spray liquid insecticides by means of an atomizer, into which air is forced by an associated plunger pump or rubber bulb. The present invention, however, resides in a device for storing gas charged liquid insecticides 10 or fungicides and in cooperating means for atomizing such charged liquids by means of the pressure developed by such gas.

The principal object of the invention is the provision of improved means for storing a gas 15 charged liquid insecticide or fungicide.

Another object is the provision of an improved container for such charged fluid insecticide; and,

Still another object is the provision of improved means readily associative with such container for spray vaporizing such charged insecticides.

Referring to the drawing:—

Figure I is a front elevational view of the device embodying my invention.

25 Figure II is a section therethru substantially along the line II—II of Figure III.

Figure III is a plan view of the device shown in Figure I.

Referring to the drawing in detail:—

30 The device embodying the invention comprises a bottle 1, having walls of such thickness as to withstand the pressure of a gas dissolved or adsorbed in a liquid insecticide or fungicide shown as contained in the bottle and designated by the letter L, gas in the space above the liquid 35 being designated by the letter G. This bottle 1 is closed by means of a stopper 2, preferably of resilient rubber, through the center of which a tube 3 projects. This tube is cemented or 40 otherwise firmly held in the stopper. The lower open end of the tube extends nearly to the bottom of the bottle and the upper end projects somewhat above the surface of the stopper 2. This upper end of the tube 3 is sealed with a disk 45 4 of soft and easily penetrable metal, such as tin or lead. The atomizing means, forming a part of the invention, comprise a plastic molded body 5 of such shape so as to snugly hold the bottle 1. This bottle 1 is resting on a gasket 6 50 of resilient rubber which is interposed between the body 5 and the bottom of the bottle. Another resilient gasket 7 is positioned between the neck end of the bottle 1 and the flat bottom of an annular depression 8, in an atomizer head 9 which, by means of a flange 10, is threaded on

the molded body 5. In assembling the head 9 it is desirable that the gaskets 6 and 7 be somewhat compressed to form a gas tight joint around the neck end of the bottle and exert frictional forces on the threads to prevent the head from 5 becoming accidentally unscrewed from the casting. A pair of counterbore-like depressions 11 and 12 are molded in the head 9 directly above the bottle opening. A shoulder 13, formed by the junction of the molded depressions 11 and 12, 10 is angularly faced and forms a seat for a conical valve head 14 whose stem 15 projects upwardly through a vertical hole in the head 9. A straight walled, flat bottomed, counterbore-like depression 16 surrounds the valve stem hole in the upper face of the head 9, and a flanged rubber gasket 17 is seated therein surrounding the stem 15. The flange of this gasket 17 forms a packing around the stem 15 of the valve head 14. A spring 18 circumferentially mounted on the stem 20 by exerting pressure against the underside of a button 19, fixed to the extending portion of the stem 15, holds the valve head 14 against the shoulder 13, thus forming a gas tight closure. Since an equal amount of pressure is exerted by 25 the lower end of the spring against the flange of the rubber gasket 17, this flange is slightly extruded thus increasing its packing action of the stem 15.

The flat surface of the valve head 14 is provided with a sharp metallic spur 20, in such position, so that when the button 19 is pressed an amount sufficient to somewhat compress the gasket 17, the spur 20 will penetrate the seal 4 in the end of the tube 3, thus breaking the seal of 35 the bottle 1.

The counterbore-like depression 12, in the interior of the atomizer head 9, is provided with a narrow molded pocket 21 and a small hole 22 extends between the pocket and the exterior of 40 the atomizer head. To aid in atomizing the liquid a thin metallic pin 23, extending through the hole 22, is studded in the atomizer head 9 and its slightly bulbous head 24 is positioned in the outer end of the hole 22 flush with the exterior of the head.

When the filled bottle 1 has been inserted in the molded body 5 and the atomizing head 9 has been securely threaded thereto, pressure is applied to the push button 19 until the gasket 17 50 is slightly depressed, thus causing the spur 20 to penetrate the sealing disk 4. Reducing the pressure on the button 19 slightly so that its bottom rests on the uncompressed surface of the gasket 17 releases some of the dissolved gas in 55

the bottle, thus creating a pressure and forcing some of the liquid contents through the opening formed when the valve head 14 is forced from the angular shoulder 13 by pressure on the button 19 and thence, with increased velocity, through the bore 22. The head 24 of the pin 23, in the well known manner, aids in the atomizing process.

While in this embodiment the container is shown in the form of a bottle, it will be readily seen that a metal container, such as the widely known "tin can", may be advantageously employed. When such is the case, the sealed tube 3 projects through the end of the can to which it is soldered or otherwise sealed. It will also be seen that the embodiment of the invention herein disclosed is well adapted to fulfill the objects primarily stated; it is to be understood, however, that the invention is susceptible to variation, modification and change within the spirit and scope of the subjoined claim.

Having described the invention, I claim:

In a device of the class described, in combination, a sealed inner container charged with an

insecticide liquid and a pressure creating gas, said sealed inner container having a puncturable seal and a conduit leading from said puncturable seal to said insecticide liquid, a casing comprising a hollow body of molded plastic material to receive said sealed inner container and a cover of molded plastic material, there being a joint between said cover and said sealed inner container when the device is assembled, means for rendering the joint between said cover and said container fluid tight, said body and cover having cooperating threads for holding said body and cover in assembled relation and exerting clamping pressure upon said container, said cover having a passage formed therein which passage terminates at one end in an atomizing nozzle, a spur mounted within said passage and adapted to puncture said puncturable seal, a valve within and normally closing said passage, and means mounted in said cover and connected to said valve and manually operable from the exterior of said cover to open said passage and cause said liquid to be atomized from said nozzle.

HUBERT D. BENNETT.
